United States Patent

Des. 239,718
Patented Apr. 27, 1976

239,718

PROGRAMMABLE PRINTER

Howard A. Powers, Medfield, Mass., assignor to
Modicon Corporation, Andover, Mass.

Filed Feb. 19, 1974, Ser. No. 443,200

Term of patent 14 years

Int. Cl. D14—02

U.S. Cl. D26—5 C

FIG. I

FIG. 2

FIG. 3

FIG. 4

FIG. 5

FIG. 6

FIG. 7

FIG. 1 is a top view of a programmable printer embodying my new design;

FIG. 2 is a front view of the programmable printer of FIG. 1;

FIG. 3 is a right side view of the programmable printer of FIG. 1;

FIG. 4 is a left side view of the programmable printer of FIG. 1;

FIG. 5 is a back view of the programmable printer of FIG. 1;

FIG. 6 is a bottom view of the programmable printer of FIG. 1; and

FIG. 7 is a perspective view from the top and one side of the programmable printer of FIG. 1.

I claim:

The ornamental design for a programmable printer, substantially as shown and described.
